UNITED STATES PATENT OFFICE.

WILLIAM AUSTIN DARRAH, OF MANSFIELD, OHIO.

INCANDESCENT LAMP.

1,252,372.

Specification of Letters Patent. Patented Jan. 1, 1918.

Application filed July 31, 1914. Serial No. 854,362.

To all whom it may concern:

Be it known that I, WILLIAM AUSTIN DARRAH, a citizen of the United States, residing at Mansfield, in the State of Ohio, 5 have invented certain new and useful Improvements in Incandescent Lamps, of which the following is a specification.

This invention relates to incandescent lamps and while in the present state of the 10 art, it is particularly applicable to the non-vacuum, or gas-filled lamps, it may also be applied to other types of incandescent lighting devices.

The object of this invention is to increase 15 the efficiency of incandescent lamps by reducing the loss of heat by the continuous passage of relatively cool gas over the relatively hot filament, or radiating element of the lamp.

20 This may be accomplished by surrounding the heated radiating element by a transparent envelop, or semi-envelop, of material which will safely withstand the temperatures to which the gases, heated by the 25 radiating element, will subject it. The envelop may be shaped like an inverted cup opened at the bottom, or it may be entirely inclosed, in which case it may, if desired, be surrounded by an evacuated heat insulating space, or any modification of these 30 shapes may be used.

It will be obvious that by thus retaining the gases, which are intensely heated in the presence of the radiating element, that the 35 cooling effect which they exert upon the radiating element will be materially lessened and the efficiency of the lamp will be proportionally increased.

It is well known that any solid body in 40 the path of the gases from the radiating element is normally rapidly darkened by a deposit caused by the radiating element and probably composed of a mixture of tungsten and tungsten compounds in the case of 45 tungsten filament lamp and in general, by a mixture of a material which forms the radiator and compounds of that material.

Since the dark deposit is rather opaque, its density rapidly increasing with the 50 period of operation of the lamp, it will be obvious that this deposit would make it impracticable to operate a lamp equipped with an envelop, as here described, unless some

means are provided to overcome the difficulties caused by the deposit. This, I have 55 accomplished by coating the inside of the transparent envelop, or economizer, with a compound which, at the temperatures encountered under operating conditions, is able to combine with the dark deposit, the 60 resulting material being transparent.

I have found that if the surface of the transparent economizer, which is exposed to the deposit, is coated with a fusible material containing a decolorizer, that the deposit may be absorbed as rapidly as it is formed, thus substantially reducing the light absorption which would otherwise take place. As there are many substances and 65 combinations of substances which will accomplish this result, I do not wish to be confined to any single material or combination of materials for the active portion of the economizer, but for purposes of illustration, will describe a few of the substances 70 which may be used. The particular material chosen will depend upon such factors as the position of the material; its operating temperature; the size, nature and temperature of the economizer; the material 75 of the filament or radiator; the nature of the gas present, and other factors.

It is well known that tungsten and salts of tungsten in a borax bead in the oxidizing flame give a colorless, transparent bead. 80 Microcosmic salt, and various other fluxes, (for the beads may be classed as fluxes), act in a similar manner. On the contrary if tungsten or salts of tungsten are heated in an inert or reducing atmosphere in these 85 beads the resultant bead is colored. If, however, an oxidizing material, itself colorless, is added to the borax or other bead, then even if heated in an inert atmosphere the bead may be made colorless. As a specific 90 example, potassium nitrite and borax properly mixed, and melted will give a transparent bead with metallic tungsten and its salts even in an inert atmosphere.

By way of illustration, if we have an electric lamp containing hot or vaporized tungsten in any form, such for example as a filament or electrodes, there must then be some disintegration of the hot body which will naturally condense upon the cooler walls of 105 the lamp. If, however, the deposit falls

upon a substance, as for example a borax bead containing potassium nitrate, it will be absorbed and oxidized to a colorless compound, thus leaving the bead substantially 5 as transparent as before. If, now, instead of using a borax bead, the fused material be spread over any light transmitting surface the result is the same, and the surface will not lose its transparency due to the collection 10 of soot or tungsten material. It should be understood that while I have confined the description to tungsten and certain fluxes and compounds, yet the invention is much broader than this, and applicable to fluxes 15 and agents equivalent to the oxidizing agent for almost any material which may be used as a radiator. I am aware that it is old to add to a lamp certain halogen containing materials but it should be noted that none 20 of these function as the compound which I add directly to the light transmitting surface. In general terms the borax or equivalent may be called a flux and the oxidizing agent or its equivalent a decolorizer.

25 With a tungsten filament in nitrogen, or an inert gas of the argon series and a quartz economizer, I have found that potassium nitrite, or nitrate, previously fused at a temperature slightly higher than the operating 30 temperature of the economizer, is satisfactory. This material may be somewhat improved by the addition of such fluxes as borax, boric acid, sodium silicate, or microcosmic salt in various proportions. Magnesium nitrite will allow the operation of the 35 economizer at still higher temperatures and at the proper temperatures, the various chlorates, peroxids, perborates and other oxidizing compounds are satisfactory.

40 An addition of an alkali hydrate, previously fused, may be made to secure somewhat more rapid action. Boric acid is a very useful oxid for this purpose as a flux, especially when mixed with some of the more 45 stable chlorates, oxids, perborates, etc. It will thus be evident that there are many combinations possible for accomplishing this result. The required properties of the material being mainly, that it shall be light-transmitting and shall be able to combine 50 with the deposit from the filament with the aid of the temperature reached in operation to form a substance which is light-transmitting. It will be evident that, if properly constructed, the entire economizer may 55 be formed from the active material.

Referring to the drawings, Figure 1, is an elevation partly in section of one form of economizer applied to a lamp, while Fig. 2 60 shows a modification of the economizer which, if desired, may be surrounded by an evacuated space for heat insulation, or the surrounding space may be filled with a gas.

In the figures, 1 represents the lamp base;

2 the outer bulb and 3, the stem through 65 which the leads enter. The filament coil 4 is shown supported by stays 5. Reference #6 indicates the economizer, and 7, the active surface, while 8 illustrates how a second economizer may be placed outside the first, 70 if desired, to still further reduce the heat loss. It will be obvious that if desired, the walls of the lamp bulb may serve as the economizer surface and be coated with the active material.

75 Having fully described my invention, I wish to secure the following claims:

1. An incandescent lamp having a surface containing material composed of flux and an oxidizing agent.
2. In an incandescent lamp a light transmitting surface containing fusible material composed of a flux and an oxidizing agent.
3. In an incandescent lamp, a surface adjacent to the radiator, said surface being 85 coated with an oxidizing flux for tungsten.
4. In an incandescent lamp, a pocket for gases heated by the radiator, said pocket containing a flux material for absorbing and rendering light transmitting a deposit thereon caused by said radiator.
5. In an incandescent lamp, a surface heated by the radiator, and containing flux for holding and rendering light transmitting the deposit thereon caused by said radiator.
6. In an electric lamp a radiator, a light transmitting surface, a portion of which contains a glass like body having the property of forming a solid transparent compound with a deposit caused by the radiator.
7. In a gas filled incandescent lamp, a pocket for retaining gases heated by the filament, said pocket being coated with a flux for combining with and holding the deposit 105 thereon caused by the filament.
8. An electric lamp comprising a radiator, a transparent surface heated by said radiator, and coated with a glass-like material containing compounds for combining with 110 and rendering transparent a deposit thereon caused by said radiator.
9. In an electric lamp a surface coated with a material containing a flux and a decolorizer.
10. An electric lamp containing incandescent tungsten, a transparent container, and a coating on said container of a flux and a decolorizer.
11. An electric lamp having a radiating 120 element and a light transmitting surface containing a flux for said radiating element and a decolorizer for said radiating element.
12. In an electric lamp, a pocket for gases heated by the radiator, a light transmitting 125 surface at the pocket containing a material and a flux for absorbing and decolorizing the deposit from the radiator.

13. A coating for a light transmitting surface of an electric lamp, said coating comprising a flux material and a decolorizing material.

14. In an electric lamp a light transmitting surface composed of a flux and a decolorizer.

In testimony whereof I affix my signature in presence of two witnesses.

WILLIAM AUSTIN DARRAH.
